(57) **CLAIM**

The ornamental design for a multi-cooker and a container for a multi-cooker as shown and described.

DESCRIPTION

FIG. 1 is a front, top, right perspective view of a multi-cooker and container for a multi-cooker, according to our new design;

FIG. 2 is a rear, bottom, left perspective view thereof;

FIG. 3 is a front side elevation view thereof;

FIG. 4 is a rear side elevation view thereof;

FIG. 5 is a left side elevation view thereof;

FIG. 6 is a right side elevation view thereof;

FIG. 7 is a top plan view thereof; and,

FIG. 8 is a bottom plan view thereof.

Broken lines of equal length dashes in the figures illustrate portions of the multi-cooker and container for a multi-cooker that form no part of the claimed design. The shade lines in the Figures show contour and not surface ornamentation.
